US0D1007530S

(12) **United States Design Patent** (10) **Patent No.:** **US D1,007,530 S**
(45) **Date of Patent:** **** Dec. 12, 2023**

(54) **DISPLAY SCREEN OR PORTION THEREOF WITH A GRAPHICAL USER INTERFACE**

(71) Applicant: **Aristocrat Technologies Australia Pty Limited**, North Ryde (AU)

(72) Inventors: **Gary Penacho**, Henderson, NV (US); **Patrick Finch**, Las Vegas, NV (US)

(73) Assignee: **Aristocrat Technologies Australia Pty Limited**, North Ryde (AU)

(**) Term: **15 Years**

(21) Appl. No.: **29/824,906**

(22) Filed: **Jan. 27, 2022**

Related U.S. Application Data

(63) Continuation of application No. 29/725,268, filed on Feb. 24, 2020, now Pat. No. Des. 944,268, which is a continuation of application No. 29/685,943, filed on Apr. 1, 2019, now Pat. No. Des. 879,827, which is a continuation of application No. 29/615,031, filed on Aug. 25, 2017, now Pat. No. Des. 852,830.

(57) **CLAIM**

We claim the ornamental design for a display screen or portion thereof with a graphical user interface, as shown and described.

DESCRIPTION

FIG. 1 is a front view of a first embodiment of a display screen or portion thereof with graphical user interface, showing the new design;

FIG. 2 is a second embodiment thereof; and,

FIG. 3 is a third embodiment thereof.

The outermost broken line illustrates a display screen or portion thereof and forms no part of the claimed design. The remaining broken lines represent elements of the display screen or portion thereof with a graphical user interface that form no part of the claimed design.

1 Claim, 3 Drawing Sheets
